UNITED STATES PATENT OFFICE.

FRANK W. ANDREWS, OF DAYTON, OHIO, ASSIGNOR, BY MESNE ASSIGNMENTS, TO
FRIGIDAIRE CORPORATION, A CORPORATION OF DELAWARE.

REFRIGERATING APPARATUS.

Application filed April 28, 1927. Serial No. 187,349.

This invention relates to refrigerating apparatus, particularly to the construction and arrangement of cooling units in refrigerating cabinets of the household type.

5 One of its objects is to provide an improved cabinet which will effectively cool circulating air to conserve food and at the same time rapidly freeze ice.

Another object is to increase the period 10 during which the cabinet may be operated without defrosting.

Another object is to construct the ice-making compartments so that air can freely circulate around them. Still another object is 15 to minimize the likelihood of freezing the ice-making receptacles to the ice-making compartments.

Further objects and advantages of the present invention will be apparent from the following description, reference being had to the accompanying drawings, wherein a preferred form of embodiment of the present invention is clearly shown.

In the drawings:

25 Fig. 1 is a front elevation of a cabinet constructed in accordance with my invention;

Fig. 2 is an enlarged section of the cooling compartment of a cabinet, the cooling unit therein being shown in section on the line 30 2—2 of Fig. 3;

Fig. 3 is a side elevation partly in section of a cooling unit removed from the cabinet;

Fig. 4 is a rear elevation of the cooling unit;

35 Fig. 5 is an enlarged horizontal section of a portion of the cooling unit taken on the line 5—5 of Fig. 1;

Fig. 6 is a vertical section thru a portion of the cooling unit on the line 6—6 of Fig. 3;

40 Fig. 7 is a portion of an enlarged vertical section thru an ice-making receptacle taken on the line 7—7 of Fig. 1; and

Fig. 8 is a perspective view of a portion of the apparatus removed from the evaporator.

45 Referring to Figs. 1 and 2, 10 is a refrigerating cabinet which may be of conventional structure having a cooling compartment 11, a storage compartment 12, doors 14, and a machine compartment 15. The cooling and storage compartments may be conveniently provided by dividing the interior of the cabinet by an L-shaped partition 16 having openings 17 and 18 for the circulation of air. A cooling unit generally denoted by 20 is placed

within the cooling compartment, supported 55 by straps 21 from the top wall of the cabinet and cools the air within the cooling compartment setting up circulation thru the openings 17 and 18 in the well known manner. A baffle 22 is placed above the opening 18 to 60 prevent moisture dripping into the storage compartment.

In accordance with my invention I may construct the cooling unit as follows. A horizontal header 23 is provided with a number of 65 depending vertical conduits in the form of tubes 24 and 25 which circulate liquid refrigerant supplied to the header thru a connection 26 and maintained at a constant level 27 in the header by a valve operated by a float 70 28. The evaporation of liquid refrigerant in the tubes produces refrigeration in the well known manner. The liquid refrigerant may be supplied to the connection 26 thru a conduit 26^a and gaseous refrigerant may be withdrawn thru a conduit 29 having a connection 29^a, by any suitable refrigerating apparatus, (for example, that shown in the patent to Robert G. Osborn No. 1,556,708, October 13, 1925) which may be disposed within the machine compartment 15.

As shown in Figs. 2 and 4, the conduits 24 are placed closer to the central vertical plane of the header than the conduits 25 and as shown in Fig. 5, the conduits 24 and 25 alternate along the length of the header. The conduits may be formed in any suitable manner but their production and assembly are considerably facilitated if each conduit 24 is connected to a companion conduit 25 by a horizontal portion 30. An easily formed loop of pipe connected at both ends to the header, thus provides one conduit 24 and one conduit 25.

The conduits 24 form a wall permeable 95 to air currents, which defines a freezing space 40 within and surrounded by the space occupied by the conduits 25. Within the freezing space I place any suitable number of compartments for ice-making receptacles. As shown in Fig. 8, each compartment is in 100 the form of a rectangular sleeve 41, preferably made of metal of good thermal conductivity, such as copper. One end of the sleeve has an outwardly flaring portion or flange 42. The compartments fit snugly within the freezing space, maintaining a thermal contact with the tubes 24. The compartments

are held in place in the freezing space as follows. (Refer to Figs. 3 to 5). The desired number of compartments are assembled in spaced relation and secured together by being soldered to a back plate 43 and a pair of L-shaped braces 44. A leg 45 is attached to the lowermost compartment and is adapted to rest on the horizontal portions 30 of the evaporator tubes. The braces 44 have 10 holes to receive bolts 46 which pass thru brackets 47 soldered to some of the tubes 25. The L-shaped braces 44 are clamped against the brackets 47 by the bolts 46, acting thru a front plate 48 (to be described later) which 15 presses against the flanges 42. Gaskets 50 and 51, of thermal insulation (such as cork) are placed between the front plate and the flange 43 and bolts 46, respectively.

The spaces 55 between the compartments 20 permit air to circulate freely over the tubes 24 and 25 and in contact with the compartments. The back plate 43 acts as a closure for the end of each compartment, and as a closure for the spaces 55 between the compartments, thus confining circulating air to such spaces and preventing it from escaping thru or between the ends. To permit air to circulate thru the compartments, I provide holes 56 in each side member 57 of the 25 compartments. The top of each compartment is imperforate and acts as a shield to protect the contents of the compartments from moisture dripping from parts above, during defrosting.

30 The bottom of each compartment is provided with a number of elevations 58 to support an ice-making receptacle, and a number of drain openings 59. Ice-freezing trays or pans 60 are placed in the compartments, the elevations 58 holding them above the bottom and permitting the circulation of air beneath them. The pans are of such dimensions that a considerable space for the circulation of air is provided between top, bottom, sides and 45 ends of the pans and the corresponding walls of the compartments. See Figs. 2 and 3.

When placing ice pans in freezing compartments, water is likely to be spilled on the bottom of the compartment, which freezes 50 the pan to the compartment and makes its removal very difficult. My invention avoids this annoyance by supporting the pans on the elevations 58. If water is spilled it will immediately drain from the floor of the compartment thru holes 59. Consequently there 55 can be no water to freeze at the points of support of the pan.

The front plate 48 heretofore mentioned has openings registering with the compartments for the passage of ice pans, each opening being surrounded by a flange 61. This plate acts as a closure for the spaces 55 between the compartments at the front end just as does the plate 43 at the back end.

35 In order to close the openings in the front

plate, each tray carries a bracket 62 to which is secured a cover plate 63, clamped between a handle 64 and the bracket by a bolt 65. An insulating washer 66 between the plate and bracket prevents transfer of heat from the 70 cover plate to the tray. When the tray is in position in the compartment, the cover plate closes the opening, and the bracket insures the tray being at a sufficient distance behind the front plate to provide an air-circulating 75 space.

The insulating gaskets 50, 51 and 66, mentioned above prevent frosting of the front plate 48 and cover plates 63, and the consequent annoyance of moisture dripping on the 80 handles during de-frosting of the cooling unit. The front plate may also be suitably shaped as at 70 to act as a shield to protect the handles from moisture dripping from the conduit connections 26 and 29^a. Moisture 85 dripping from these will be prevented from entering the freezing compartments by the flanges 63 and gaskets 48.

As shown in Fig. 2 the cooling unit is placed in the cabinet with the header below 90 the level of the opening 17 and with the conduits 25 extending in fairly close proximity to the walls of the cabinet and partition 16. The conduits 25 are thus entirely exposed to air circulating between the openings 17 95 and downwardly over the cooling unit and therefore effectively cool this air which in turn cools the storage compartment. Due to the staggered relations of the conduits 24 and 25, shown best in Fig. 5, and the openings 45 in the sleeve, air cooled by the tubes can circulate freely over and around the ice trays to absorb heat from and freeze the water in the trays.

As shown best in Fig. 1, the front plate 105 48 occupies substantially the entire length and width of the cooling compartment, thus acting as a partition, which cooperates with the L-shaped partition 16 to form the cooling compartment and completely enclose the cool- 110 ing unit.

While the form of embodiment of the present invention as herein disclosed, constitutes a preferred form, it is to be understood that other forms might be adopted all 115 coming within the scope of the claims which follow.

What is claimed is as follows:

1. A cooling unit for refrigerating apparatus comprising refrigerant conduit means 120 defining a freezing space, and a compartment within the space having openings to permit the circulation of air thru the compartment.

2. A cooling unit for refrigerating apparatus comprising refrigerant conduit means defining a freezing space, and a compartment within the space having openings therein, the conduit means, compartment, and openings being arranged to permit the cir- 125 130

culation of air over the conduit means and thru the compartment.

3. A cooling unit for refrigerating apparatus comprising refrigerant conduit means defining a freezing space, and a compartment within the space thermally connected to the conduit means and having openings therein, the conduit means, compartment, and openings being arranged to permit the circulation of air over the conduit means and thru the compartment.

4. A cooling unit for refrigerating apparatus comprising conduit means forming permeable walls defining a freezing space, and a compartment located in the freezing space, the compartment having openings arranged to permit the circulation of air thru the walls and compartment.

5. A cooling compartment for refrigerating apparatus comprising a compartment for an ice-making receptacle, means for cooling the compartment, said compartment having an imperforate top and a perforate bottom, and means for supporting an ice-making receptacle in the compartment above the bottom.

6. Apparatus as defined in claim 1 wherein is provided means for supporting an ice-making receptacle in the compartment above the bottom thereof.

7. Apparatus as defined in claim 1 wherein are provided means for supporting an ice-making receptacle in the compartment above the bottom thereof and drain open-

ings in the bottom of the compartment adjacent the supporting means.

8. Apparatus as defined in claim 1 having means for supporting an ice-making receptacle above the bottom of the compartment, said means being adapted to permit the circulation of air thru the compartment and beneath a receptacle placed on said means.

9. Apparatus as defined in claim 1 having an ice-making receptacle within the compartment and means for supporting the receptacle above the bottom of the compartment, the receptacles and compartment being of such relative dimensions as to leave spaces for the circulation of air entirely around the receptacle within the compartment.

10. Refrigerating apparatus comprising a cabinet having a cooling compartment and a storage compartment, said compartments being interconnected to permit the circulation of air between them, a cooling unit placed within the cooling compartment adapted to effect the circulation of air thru the compartments, the cooling unit having a portion exposed to the circulating currents to cool the latter and a portion defining a freezing space within said first-mentioned portion, and a compartment for an ice-making receptacle within the freezing space having openings for the circulation of air thru said freezing space and compartment.

In testimony whereof I hereto affix my signature.

FRANK W. ANDREWS.
